H. GREEN

RADIO LOUD SPEAKER

Filed June 18, 1926

Inventor
Henry Green
By M. Lee Holmes
Attorney

UNITED STATES PATENT OFFICE.

HENRY GREEN, OF UNION HILL, NEW JERSEY, ASSIGNOR TO HERMANN FISCHER, OF NEW YORK, N. Y.

RADIO LOUD SPEAKER.

Application filed June 18, 1926. Serial No. 118,957.

The object of this invention is to provide a radio loud speaker employing a novel form of connection intermediate the induction spool, magnet poles and diaphragm in order to obtain greater efficiency in the vibration of the diaphragm, with increased volume and avoidance of sound distortion.

The invention will be understood by reference to the accompanying drawings, in which—

Figure 1 is a fragmentary sectional plan view of the loud speaking unit showing an embodiment of the invention applied thereto, the same being on the line 1—1, Figure 2;

Figure 2 is a side elevation of the same, the diaphragm supporting members being shown in section, and

Figure 3 is a front elevation of the device illustrated in Figure 1;

Figure 4 is a bottom plan view of the vibratory connection intermediate the diaphragm and the magnet poles, and

Figures 5, 7 and 9 are similar views of different modifications;

Figure 6 is an elevation of the device shown in Figure 5;

Figure 8 is an elevation of the device shown in Figure 7;

Figure 10 is a side elevation of the device shown in Figure 9, and

Figure 11 is a front elevation of the same.

In Figures 6, 8 and 10 the connection device is shown attached to a diaphragm.

Referring to the drawings, 1 indicates a supporting plate forming part of a loud speaker unit which includes the connected rings 2 and 3 which clamp between them a diaphragm 4. Mounted upon plate 1 is a magnet (not shown) and an induction spool 5, the windings extending about a central supporting member 5* which is provided with a central slot or space 6 (Figure 3) for the reception of the vibratory tongue or plate 7. At the top of this plate is the operative end of angular magnet pole piece 8, a co-operating magnet pole piece 9 being disposed below the vibratory plate.

In former constructions the vibratory plate has been connected to the centre of the diaphragm by a needle, and the plate has been supported within the spool by upper and lower pins which permit the plate to have a rocking motion on substantially a centrally disposed axis. One defect in such construction is that a lateral force is exerted

upon the needle in addition to the endwise force, which causes the diaphragm to abnormally resist the normal motion of the needle and the resultant lateral stress upon the diaphragm causes a sound distortion effect.

A further objection to such needle connection is that the latter bears upon a very small area only at the axis of the diaphragm, and frequently a greater range of movement is permitted in the needle and in the diaphragm than is required for a correct vibration. There is too much spring in the needle and in the resultant diaphragm movement. I have discovered that when the diaphragm is given short and rigidly applied movements as contrasting with the springy action of a needle, and the force exerted upon the diaphragm is applied over a substantial area (which may not be confined to the axis of the diaphragm) very much better results are obtained.

My connection intermediate the diaphragm and the vibratory plate consists of a short, stiff, relatively wide member 10 which may be described as a plate, although it is not necessarily flat. At its contact end with the diaphragm it is provided with a tongue, and in the drawings I have illustrated four different forms of this tongue. In the form illustrated in Figures 2, 3 and 4, the tongue comprises two curved members 11, 11*, the plate and the tongue on a line meeting the diaphragm forming a substantially cylindrical member as viewed in Figure 4. In Figures 5 and 6 the tongue 12 is formed in reverse curves of wide area. In Figures 7 and 8 the tongue 13 is similar in form to that of Figures 5 and 6, but all substantially less spread. In Figure 9 the tongue 14 comprises two straight members 14.

In Figures 4, 5 and 9, each vibratory plate 7 is provided with a short front extension 7* for securing to a rigid member, such as a member of the induction spool. In Figure 7 the vibratory plate 7 is provided with the pintles 15, for pivoting the plate in the induction spool, and the plate is formed with the front extensions 16 to be supported on plate 1 by means of the posts 17. It will be seen that the tongue 13 is placed intermediate posts 17 and pintles 15. The vibratory plate therefore acts as a primary diaphragm and the diaphragm 4 as a secondary diaphragm. This construction is similar to that

in Figure 5 in that the vibratory plate shown in said figure is provided with an extension 18 to be supported by a post 19, the plate 7 therefore being held at both ends for action as a primary diaphragm.

It will be understood that the mounting for the diaphragm, illustrated in the drawings, forms no part of the present invention, and a mounting may be employed or omitted as desired.

Having described my invention what I claim and desire to secure by Letters Patent is as follows:

1. In a radio loud speaker, an induction 15 spool, a magnet, a vibratory plate supported for vibration by said magnet, a diaphragm, a tongue extending transversely of the diaphragm and connected therewith and a rigid connection between said tongue and the vibratory plate.
2. In a radio loud speaker, an induction spool, a magnet, magnet poles, a vibratory plate adapted to be acted upon by said poles, a diaphragm, and a plate-like member con-

necting the diaphragm and the vibratory plate.

3. In sound amplifying apparatus, a magnet adapted to receive radio impulses, a diaphragm, a connection intermediate said diaphragm and the magnet comprising a vibratory plate, a tongue extending transversely of the diaphragm and connected thereto and a plate-like member directly connecting the tongue and the plate.

4. A device constructed in accordance with claim 1 in which the vibratory plate is supported at spaced points at opposite sides of the connection with the tongue, so that the plate acts as a primary diaphragm.

5. In sound amplifying apparatus, a connection intermediate a magnet and a diaphragm consisting of a vibratory plate having a plate extension at right angles thereto constituting a stiff, plate-like member for direct connection to the diaphragm.

In testimony whereof, I have signed my name to this specification.

HENRY GREEN.
